FIG. 1.

INVENTOR.
Eben Moody Boynton
By A. M. Webster,
Atty.

UNITED STATES PATENT OFFICE.

EBEN MOODY BOYNTON, OF WEST NEWBURY, MASSACHUSETTS.

FREIGHT-CAR FOR BICYCLE-RAILWAYS.

SPECIFICATION forming part of Letters Patent No. 393,961, dated December 4, 1888.

Application filed July 26, 1888. Serial No. 281,128. (No model.) Patented in England March 8, 1887; in Spain June 2, 1887; in Belgium June 30, 1887; in France August 30, 1887; in Brazil October 13, 1887; in Austria-Hungary October 30, 1887; in Norway December 22, 1887; in New South Wales March 7, 1888; in Victoria March 7, 1888; in New Zealand March 7, 1888, and in India April 2, 1888.

To all whom it may concern:

Be it known that I, EBEN MOODY BOYNTON, a citizen of the United States, residing at West Newbury, in the county of Essex and State of Massachusetts, have invented certain new and useful Improvements in Freight-Cars for Bicycle-Railways, (patented in Great Britain March 8, 1887; in Spain June 2, 1887; in Belgium June 30, 1887; in France August 30, 1887; in Brazil October 13, 1887; in Austria-Hungary October 30, 1887; in Norway December 22, 1887; in New South Wales March 7, 1888; in Victoria March 7, 1888; in India April 2, 1888, and in New Zealand March 7, 1888;) and I do hereby declare the following to be a full, clear, and exact description of the invention, such as will enable others skilled in the art to which it appertains to make and use the same.

My invention relates to the construction of railway-cars especially adapted for the bicycle-railway system, the principle of which is a single line of supporting-rails below and a single line of guiding-rails overhead, the rolling-stock being adapted to run on said upper and lower rails, the overhead guide-rail being employed to retain the cars in a vertical position upon the lower or supporting rail. The motive-power for transporting cars in this system is clearly described and claimed in my Letters Patent No. 359,008, dated March 8, 1887. The rolling-stock in the bicycle system is preferably constructed of such width that when two trains are running on the rails of an ordinary gage railway they can pass each other going in either direction without the slightest danger of contact. The desired results are accomplished by having the entire weight of the locomotive and the cars supported upon central wheels placed longitudinally to the car, one running upon a single supporting-rail of ordinary or other suitable construction, said rolling-stock being retained in the vertical position by means of wheels arranged above said locomotive and cars in such position that they will engage the overhead or guide rail, which is suitably supported above the lower rail.

My present invention relates to certain specific improvements in the construction of freight-cars, whereby they are made self-dumping, thus making this form of cars especially useful in the transportation of grain, coal, gravel, or any similar loose material. In order to accomplish these results in the simplest manner possible and to produce a car in which the original cost of construction shall be reduced to the minimum, which shall be durable, and in which special parts shall not be liable to get out of repair, I have devised the novel self-dumping car, of which the following description, in connection with the accompanying drawings, is a specification, letters being used to denote the several parts.

Figure 1 is a side elevation of my novel car, showing also a section of the upper and lower rails; Fig. 2, a cross-section on the line *x* *x* in Fig. 1; Fig. 3, a plan view, and Fig. 4 a detail view, of the ratchet mechanism for opening and closing the side door, the ratchet-lever also serving as a locking-hasp.

*A*⁴ denotes longitudinal stringers for the lower or supporting rail; *A*⁵, longitudinal stringers for the upper or guide rail; *a*, the lower or supporting rail, and *a'* the upper or guiding rail, said rails being suitably attached to the upper and lower stringers, respectively.

The cars may of course be constructed of any suitable material. I preferably, however, use steel. The body of the car is made deepest at the center, so as to permit self-dumping at a side door, *K*², or through a sliding door (not shown) in the bottom of the car, thus allowing the contents of the car to be deposited in elevators, ships, or at any desired place. The loose freight is admitted to the car through an aperture in the top, which is covered by a sliding door, *K*, which may be operated in any suitable manner, ordinarily by a cord or wire rope, *K'*, the door being preferably arranged to slide on casters. As the door at the bottom of the car would be practically a duplicate of this one, it is not deemed necessary to illustrate both. The side door, *K*², is operated by means of a ratchet, *n*⁶, rigidly secured to the side of the

car and placed parallel to and preferably about midway between the top and bottom slide-rails, n^8 , in which the door slides. n^5 denotes a hasp secured to the door and acting to lock it by means of an ordinary staple and padlock, and which is furthermore so formed as to serve the purpose of a ratchet lever or handle, the point of said hasp or lever being suitably formed to engage ratchet n^6 , for the purpose of opening and closing the door, said ratchet serving as the fulcrum of the lever.

My improved cars are preferably provided each with four supporting-wheels, M , which travel on the supporting-rails, and with four guiding-wheels, M' , which travel under but engage the guide-rails a' .

It is not essential that four wheels be employed, as single wheels may be used instead of double wheels on each truck. The wheels are formed with inner and outer flanges, thereby forming a groove to fit and run upon the single upper and lower lines of rails. As shown in the drawings, the two wheels upon each truck upon the top of the car are journaled in suitable bearings, m , upon a yoke, M^2 , resting upon spiral springs m' , which cushion the yoke and yield sufficiently to compensate for slight irregularities in the supporting-rails, thereby holding the guide-wheels in engagement with the guide-rails at all times.

L denotes a safety device which is used in connection with the upper stringer, A^5 . This device is attached to the yoke or any suitable portion of the truck, and consists of a double bracket curving outward and then inward, each arm carrying an anti-friction roller, L' , adapted to engage the upper stringer should the guide-wheel become disengaged from the guide-rail. This device has no function whatever, except as a safety device, and only acts in the event of the derailment of the guide-wheels M' , or the sinking of the road-bed to such an extent as to cause the sinking of the guide-wheels away from the guide-rails. Should any contingency of this nature occur, the safety device will retain the train in its proper position by engagement with the up-

per stringer or the upper rail until the guide-wheels are again placed in engagement with the guide-rails, so that there is no danger whatever of derailment of the train. The perfect equilibrium of the train is at all times preserved by the engagement of wheels M 55 with the supporting-rail and wheels M' with the guide-rail, or, in the contingency of sinking of the track, by the engagement of the safety device with the upper stringer, the latter device rendering the construction perfectly safe under all circumstances.

It will of course be understood that my invention may be varied within reasonable limits without departing from the principle thereof.

I claim—

1. A freight-car for bicycle-railways having its bottom inclined downward from each end toward the middle, provided at the top with the door K , and on the side at the deepest portion of the car with the door K^2 , substantially as set forth.

2. A railway-car made deepest at the center, so as to be self-dumping, and provided at the top with a sliding door, K , and a cord, K' , whereby said door may be operated from any convenient point.

3. A self-dumping car made deepest at the center and provided with a door, K^2 , and ratchet n^6 , and a hasp, n^5 , so formed as to serve as a ratchet lever and handle.

4. The combination, with a car-door, K^2 , arranged to slide at an angle, of a hasp, n^7 , and a ratchet upon the car adapted to be engaged by said hasp, whereby the door may be opened to any desired extent.

5. The combination, with single upper and lower stringers and rails, of railway-cars having four supporting-wheels, M , and four guiding-wheels, M' , situated in the central plane of the car and below and engaging the under side of the upper stringer.

In testimony whereof I affix my signature in presence of two witnesses.

EBEN MOODY BOYNTON.
